UNITED STATES PATENT OFFICE

JESSE J. JONES, RAY W. JONES, AND GUY JONES, OF KINSTON, NORTH CAROLINA

DOORCHECK

Application filed April 30, 1929. Serial No. 359,297.

This invention relates to door checks, and has as its primary object, the provision of an improved and novel form of door checks, whereby a door may be checked and retained in a number of different positions, together with means for operating the door check in conjunction with the latch mechanism of the door.

Another salient object of this invention is to provide a novel door check operatively associated with the latch mechanism of a door which will be very simple in construction, consisting of but comparatively few parts, may be readily and easily assembled upon the door, can be manufactured at a very low cost, strong, durable and otherwise well adapted for the purpose intended.

Other objects and advantages of the invention will become apparent during a study of the following description taken in connection with the drawings, wherein:

Figure 1 is a front elevation of a door and door frame and showing the practical application of our invention therewith;

Figure 2 is a fragmentary top plan view of the same to a larger scale;

Figure 3 is a detail sectional view taken substantially on the line 3—3 of Figure 5.

Figure 4 is a sectional view taken on line 4—4 of Figure 3;

Figure 5 is a sectional view taken on line 5—5 of Figure 3.

Figure 6 is a fragmentary detail view, partly in section, and partly in elevation, of the device, and showing means for locking the device against movement when the device is in operation.

Figure 7 is a detail sectional view taken on line 7—7 of Figure 1;

Figure 8 is a detached view of the connecting bar carried by the latch mechanism.

With reference more in detail to the drawings, it will be seen that the reference character 5 designates a door frame of conventional construction, having a door 6 of any known construction hinged mounted therein as at 7—7.

At the top of the door frame 5 and adjacent one edge thereof there is secured thereto a horizontally disposed bracket 9, which is se-

cured to the frame as at 10—10 and projecting laterally of the frame as clearly shown in Figure 1. A toothed segment 11 is secured at one end thereof to the free end of the bracket 9 as at 12, and the other end of the segment 11 is secured to the frame as at 13. It is to be noted that the toothed segment 11 when so secured in place is concentric with respect to the door hinge line. Suitably secured to the top portion of the door and adjacent the hinge line thereof, is a substantially T-shaped member 14. This member 14 may be secured to the door by screws 15, or in any other suitable manner. The T-head of the member is substantially flush with the top edge of the door, and the said T-member has extending centrally therethrough a vertically disposed shaft 16 securely held against rotation therein, by means of a square headed bolt 17 secured to one end of the shaft 16 and adapted to seat within a socket 18 formed in the bottom of the T-head as clearly shown in Figure 3. A squared nut 19 is fixed as at 20 to the shaft 16 intermediate the ends of the shaft, and said nut 19 is adapted to seat within a suitable pocket 20 formed in the upper portion of the T. That portion of the shaft 16 extending beyond the T projects into this space encompassed by the rack 11 and has rotatably mounted thereon a pinion 21, and it will be noted that the pinion 21 has secured thereto as at 22—22 an open box like casing 23. A suitable spring 24 is arranged within the casing 23, and one end of this spring is fixed to the shaft 16 as at 25 and the opposite end of the spring is fixed to the wall of the casing as at 26. The pinion 21 is adapted to engage with teeth on the segment 11 and to rotate on the shaft 16 during the movement of the door to an open position, such as is illustrated for example in dotted lines in Figure 2.

A suitable cover 27 is provided with an aperture 28 through which the reduced extremity 29 of the shaft 16 projects, and a nut 30 is screw threadedly engaged with this reduced portion 29 for securing the cover in position upon the shaft. Thus the casing 23 and the cover 27 cooperate to provide a complete enclosure for the spring 24 to protect the same from the element should the

device be associated with a door exposed to the weather.

The arms 14' of the T-member 14 are preferably bifurcated as at 31, and one of the said arms 14' has pivotally mounted within its furcation a dog 32 intermediate the ends of the dog as at 33. The dog 32 is in the form of an elongated narrow member having at one end a right angularly disposed projection 34 adapted to engage the teeth of the pinion 21 as illustrated in Figure 3. Adjacent its opposite end the dog 32 has a laterally extending projection 35 slidably received in a socket 36 formed in the T 14 to limit the inward movement of the dog upon its pivotal connection. Adjacent its lower extremity the T 14 is provided with a transversely extending groove 37 extending horizontally along the inner face of the member, and this groove 37 acts as a guide for a link 38, one end of which link is secured to the free end of the dog 32 as at 39', while the opposite end of the link 38 is secured to one arm of a bell crank lever 39, as at 40. This bell crank lever 39 is pivotally mounted on the door 6 as at 41, and the other arm of the bell crank has an elongated bar 42 extending vertically therefrom. As illustrated, the bar 42 extends vertically from the bell crank adjacent the outer edge of the door 6, and the opposite end of the rod 42 has a pair of chain members 43-43 pending therefrom and secured thereto as at 44.

It is to be noted that the door 6 is provided with the usual latch member designated generally as at 45, and that the said latch member comprises the conventional door knob 46, said door knob being provided with a bar 47, the opposite end of which bar member 47 is apertured as at 48-48, whereby the ends of the respective chains 43-43 may be secured to the extremities of the said bar 47, as clearly illustrated in Figure 1. It is yet to be mentioned that the rod 42 has a slot 49 extending transversely thereof, and this slot is adapted to receive a pin 50 which pin has a flexible connection 51 with the door 6 as at 52. As shown to advantage in Figure 6 the rod 42 is adapted for slidable movement through a guide member 53 suitably secured to a door, and against the under side of which guide member the pin 50 is adapted to abut when associated with the rod as previously described, thus preventing upward vertical movement of the rod, consequently maintaining dog 32 out of engagement with pinion 21, as is obvious.

From the foregoing description then it will be seen that in operation that upon turning 60 of the knob 45 in either direction thus causing a downward movement of the rod 42 to actuate the bell crank 39, and in turn actuating the link 38 for drawing the dog 32 out of engagement with the pinion 21 thus permitting movement of the door upon its hinges.

Consequently as the door is swung upon its hinges to open position, the pinion 21 in mesh with the teeth on the rack 11 will rotate against the action of the spring thus permitting the door to swing to any desired position. When the desired open position of the door is obtained and the knob 45 on the door is released so as to cause actuation of the rod 42 and link 38 for engaging the dog with the seat of the pinion thus preventing rotation of the pinion against the action of the spring, at the same time permitting engagement of the pinion with the rack 11 to hold the door in the desired open position. As is obvious, the wider the door is swung open the tighter the spring is wound, and consequently the more power is received, so that as the door is closed, the greater power of the spring is first applied, and the said power then gradually diminishes, so as to permit a gradual and noiseless closing of the door.

While we have herein shown and described certain detail elements of construction, it is to be understood that the invention contemplates certain changes to be made therein without departing from the spirit of the invention as herein described, or the scope of the appended claims.

Having thus described our invention, what we claim as new and desire to secure by Letters Patent is:-

1. In a door check, the combination of a toothed segment adapted to be fixedly secured to a door frame, a pinion secured to a shaft and mounted upon a door and engaging said segment, a spring member operatively associated with the shaft and pinion, a pivotally mounted dog adapted to engage said pinion for locking said pinion against rotation, a bell crank mounted on the door, a link connecting the bell crank with the dog, a latch mechanism, and a rod operatively connecting the bell crank with the latch mechanism all in a manner and for the purpose set forth.

2. In a door check, the combination of a door frame and a door hingedly mounted therein, together with a latch mechanism embodying a door knob carried by the door, of a bracket carried by the door frame, a toothed segment carried by the bracket and adapted to be secured to the door frame, a T-member carried by the door adjacent the upper edge of the door, a shaft carried by said T-member, a pinion rotatably mounted on the shaft, and adapted to engage with the segment, a casing carried by the pinion and adapted to receive one end of said shaft, a spring in the casing, one end of said spring being fixed to the shaft, and the other end of said spring being secured to the casing, and means operatively associated with the pinion and the latch mechanism for locking the said pinion in mesh with the rack.

3. In a door check, the combination of a toothed segment adapted to be fixed securely

to a door frame, a pinion secured to a shaft and mounted upon a door and engaging said segment, a casing carried by the pinion, and adapted to receive one end of the shaft, a 5 spring fixed within the casing and operatively associated with said one end of the shaft, a dog, means for pivotally mounting the dog in operative relation with respect to the pinion, a bell crank pivotally carried by the door, a link connecting the dog with the bell crank, 10 a rod secured to the bell crank, guide means for the rod, a latch mechanism, means operatively connecting the rod with the latch mechanism, and means carried by the door and 15 adapted to engage the rod to prevent movement of the rod in one direction.

In testimony whereof we affix our signatures.
